BUTTON

Filed Aug. 14, 1930

UNITED STATES PATENT OFFICE

FRITZ TRÜB, OF RORSCHACH, SWITZERLAND

BUTTON

Application filed August 14, 1930, Serial No. 475,284, and in Germany August 19, 1929.

This invention relates to buttons made in two parts having means for pressing the parts against each other so as to grip the fabric from both sides. To buttons of this type the drawback is inherent that in course of time the fabric is torn by the connection between the two parts of the button getting loose, whereby the clamping effect of the button on the fabric is eliminated and the screw shank 10 of the button alone is left in engagement with the fabric which, particularly for buttons for transmitting lateral tension, such as trowser buttons for fastening the suspenders is disadvantageous.

15 This disadvantage is overcome in the button according to the invention by providing the side facing the fabric of the one part of the button with at least one circular projection and the other part with an adequate 20 number of corresponding recesses, suchwise, that the corresponding elements interengage, thereby unmovably clamping the fabric around the screw shank.

25 This arrangement enables to provide the button, when serving as a trowser button for the purpose hereinbefore described with a removable hook for attaching the connecting bands on the underwear thereto.

In the drawings several embodiments of 30 the invention are illustrated by way of example, in which

Figs. 1 and 2 each show a perspective view of a first constructional form of the button;

35 Figs. 3 and 4 are sections corresponding to the Figs. 1 and 2;

Fig. 5 is a cross section of this form of the button;

Fig. 6 shows a modified constructional form of the button, partly in a vertical section and 40 in side elevation respectively, and

Fig. 7 is a front elevation to Fig. 6.

The button shown in the Figs. 1 to 5 is made in two parts, a front part 1 and a rear part 2 which by means of the screw shank 3 passing through the cloth S is screwed to the part 1. For facilitating the parts being screwed together the edge 1a of the front part is serrated and the rear part is provided with a transverse slot 2a for engagement with a 50 screw driver or the like. The inner side of

the front part is formed with a circular projection 1b and the rear part is provided on its inner side with a corresponding recess 2b between which two gripping elements the cloth S is pressed, thus relieving the screw 55 3 from fastening the button on the cloth alone.

The periphery of the rear part is formed with a groove 2c enabling a springy wire hook 4 to be pressed in engagement therewith. 60 This wire hook serves for attaching the connecting bands on the underwear thereto, whilst the suspenders, in known manner, are secured to the button.

In the constructional form shown in the Figs. 6 and 7 the front part 10 is fastened to the cloth by means of a head screw 11 constituting the rear part and a sheet metal hook 12 is connected to the screw behind the head of the same. The back side of the hook 12 70 has an annular groove 12a into which extends a circular projection 10a on the inner side of the front part which is concentric to the screw and of triangular cross section, thus holding the cloth S which is pressed between these 75 two interengaging elements, so as to firmly secure the button on the cloth. The edge of the front part is serrated also and the head of the screw provided with a transverse slot.

I claim:

1. A button for attachment to cloth in two separable parts, in combination, a front part to present the aspect of a garment button, a head provided on said front part, a base formed on said front part in close proximity to said head, a rounded-off peripheral taper provided on said base at an obtuse angle, a rear part connected to said front part by screw engagement and a rim complementary to said taper formed on said rear part, and adapted to push the gripped cloth portion past the outer edge of said taper for locking said screw connection without damaging the cloth.

2. A button for attachment to cloth in two separable parts in combination, a front part to present the aspect of a garment button, a head provided on said front part, a base formed on said front part in close proximity to said head, a circumferential abutment for

the cloth provided on said base, a rear part connected to said front part by screw engagement, and a gripping face complementary to said abutment arranged on said rear part and adapted to push the gripped cloth portion past the outer edge of said base for locking said screw connection without damaging the cloth.

In testimony whereof I have signed my name to this specification.

10 FRITZ TRÜB.
